UNITED STATES PATENT OFFICE.

JOHN A. LUTHER, OF SCHENECTADY, NEW YORK.

PUNCH PRESS.

Application filed May 1, 1920. Serial No. 378,314.

To all whom it may concern:

Be it known that I, JOHN A. LUTHER, a citizen of the United States, residing at Schenectady, in the county of Schenectady, 5 State of New York, have invented certain new and useful Improvements in Punch Presses, of which the following is a specification.

The present invention relates to punch 10 presses and has for its object to provide an improved structure and arrangement in a punch press for performing certain types of operations as will be fully pointed out hereinafter.

15 For a consideration of what I believe to be novel and my invention, attention is directed to the accompanying description and the claims appended thereto.

In the drawing, Fig. 1 is a side elevation 20 of a machine embodying my invention; Fig. 2 is a plan view on a larger scale of part of the machine looking in the direction of the arrow A in Fig. 1; Fig. 3 is a side elevation on a larger scale of the die parts and the 25 feeding mechanism of the machine shown in Fig. 1, the same being shown horizontally as a matter of convenience; Fig. 4 is a sectional view of the upper die structure; Fig. 5 is a transverse sectional view of the lower 30 die structure, and Figs. 6 and 7 show an article before and after it has been operated on by the machine.

In the present instance the machine is shown as provided with dies for operating 35 on a ring 10, U-shaped in cross section, and in which a filler 11, such as an asbestos ring, has been placed as shown in Fig. 6, the dies operating to turn down the edges of the U-shaped ring as shown in Fig. 7 to form a 40 gasket. The particular gasket shown is more particularly for use in spark plugs. It will be understood, however, that my invention is not limited to this particular use but may be put to any use for which it is 45 found applicable.

Referring now to Figs. 1 to 5 of the drawing, 12 indicates the frame of a punch press having a bed 13 to which is bolted a shoe 14 which carries the lower die structure. 50 The upper die structure is carried by a reciprocating head 15 operated in the usual manner. These parts of the punch press are shown in a diagrammatic manner only and

are to be taken as typical of an ordinary punch press structure. 55

Referring to Fig. 5 the lower die structure comprises a ring 16 carried by a holder 17 and having an opening through it of a diameter substantially equal to the inside diameter of ring 10. Surrounding the opening in ring 16 is an annular groove 18 of a size to receive the rounded bottom edge of a ring 10 as shown in Fig. 6. Carried in recesses in ring 16 are two spaced spring pressed stop pins 19 which project slightly 65 above the top surface of ring 16.

The upper die structure, shown in Fig. 4, comprises a holder 20 which is fixed in reciprocating head 15 and has an axially extending opening 21 counterbored at its upper end to form a recess 22. Fastened on the lower end of holder 20 by a nut 23 is an inner die member 24 having a rounded nose 25 at the base of which is a curved forming or operating surface 26. In nose 25 is a transverse slot 27 and extending axially of die member 24 is an opening 28 which is in alignment with opening 21. Also extending transversely of die member 24 above nose 25 is an axially elongated slot 29. Pivoted in slot 27 one on each side of opening 28 are two catch fingers 30 having inwardly inclined outer surfaces 30^a and rounded shoulders 31 which project just beyond the surface of nose 25. Catch fingers 30 are pivoted adjacent their upper ends and their lower ends extend below the end of nose 25 and are connected together by a spring 32 which acts to hold the catch fingers in the position shown in Fig. 4. Surrounding inner die member 24 and movable axially thereon, is an outer die member 33 having a curved forming or operating surface 34 which is complementary to surface 26 on inner die member 25. Outer die member 33 functions as an ejector also as will appear hereinafter. Outer die member 33 is fastened to inner die member 24 by a pin 35 which extends through slot 29 and as is clear, die member 33 may slide up and down 100 on die member 24 a certain amount, downward movement being limited by pin 35 engaging the lower end of slot 29 and upward movement being limited by die member 33 engaging nut 23 or by pin 35 engaging the 105 upper end of slot 29 or both. The essential

thing is that when die member 33 reaches the upper limit of its movement curved forming surface 34 is in line with forming surface 26 so as to form an annular semi-circular 5 groove. Extending through openings 21 28 is a post 36 through the lower end of which pin 35 extends thus fastening them together. The upper end of post 36 has a head 37 located in counterbore 22 and beneath which is a spring 38 which acts to bias die member 33 to its uppermost position. However, when the punch press is at the top of its stroke, as is assumed to be the case in Fig. 4, head 37 strikes a fixed abutment as indicated by the dotted line 39 which forces die member 33 to its lowermost position as shown in Fig. 4, at the same time putting spring 38 under compression.

The operation of the die structure is as follows: Assume the die structures to occupy the positions relatively to each as shown in Figs. 4 and 5. An unfinished gasket as shown in Fig. 6 is placed in groove 18 of lower die member 16 with the open side 20 pointing upward. The upper die structure then moves toward the lower die structure and as soon as head 37 leaves abutment 39 spring 38 raises outer die member 33 to its upper position so as to bring forming surface 34 into line with forming surface 26. As the two die structures come together, nose 25 passes through the center of the gasket or ring 10 and the lower rounded surfaces of shoulders 31 strike the inner edge of the 25 gasket, the fingers turning so as to permit shoulders 31 to pass beyond the gasket. This pulls the lower ends of catch fingers 30 apart thus putting spring 32 under tension and as soon as shoulders 31 pass beyond the gasket 30 the spring pulls the lower ends of the catch fingers together again thus swinging shoulders 31 out under the gasket. As the die structures are now forced tightly together, the open edges of U-shaped ring 10 40 will be turned toward each other by curved surfaces 26 and 34, the result being a finished gasket as shown in Fig. 7. The upper die structure now moves away from the lower die structure and as it moves up the gasket 45 is caught on the upper sides of shoulders 31 and carried along with it. As the upper die structure approaches the end of its upward movement, head 37 strikes abutment 39 thereby forcing outer die member 33 50 downward on inner die member 24 which results in pushing the gasket down past shoulders 31 and off the upper die structure. The outer die member 33 acts, therefore, as an ejector for knocking the finished gasket 55 off the upper die structure. When the gasket is forced down past shoulder 31, the shoulders are forced inwardly and the catch fingers 30 are again moved away from each other putting spring 32 under tension. As 60 soon as the gasket moves beyond shoulders

31, spring 32 returns the fingers to their original positions. The die structures are then ready to operate on another gasket.

As shown in Fig. 1, the die structures lie at an angle to the vertical so the finished 70 gaskets when ejected from the upper die structure will fall out from between the two die structures into a suitable receptacle and in order to direct the gaskets from between the die structures into a receptacle, I 75 provide an inclined chute 40 having side walls 40^a. The lower end of chute 40 projects part way under the upper die structure and the upper end is fixed to a shaft 41 pivoted in two posts 42 carried by bed 13. 80 Chute 40 is held yieldingly in the position shown in Figs. 1, 2 and 3 by a spring 43 having one end fastened to a post 42 and the other end by an arm 44 projecting from shaft 41. Carried by one post 42 is a stop 85 45 which projects under arm 44 and limits the movement of chute 40 toward the upper die structure. When the upper die structure moves toward the lower one it strikes chute 40 moving it to one side and holding 90 it there, the chute turning shaft 41 in its bearings in posts 42 and putting spring 43 under tension, and when the upper die structure moves back again spring 43 will bring chute 40 back under it in time to catch the 95 gasket ejected from the upper die structure and direct it from between the die structures into a receptacle.

When the punch press is operating, the upper die structure is of course, moved continuously into engagement with and away from the lower die structure and on each stroke it can complete the formation of a gasket. Unfinished gaskets as shown in Fig. 6 may be successively placed on the lower die 100 structure, by hand but preferably I provide an automatic means for feeding gaskets to the lower die structure, one on each stroke of the press. For this purpose I provide a table 48 adjacent the punch press and on it 105 is arranged an endless belt 49 carried by rollers 50 which are supported by standards 51. Adjacent one side of belt 49 is a hopper 52 for holding a supply of unfinished gaskets. Hopper 52 is open on the side next 110 to the belt, and leading from the bottom edge of such side down to the edge of belt 49 is an inclined wall 53. Along the edge of belt 49 on the side opposite hopper 52 is a strip 54 which projects above the surface of 115 the belt and serves as a stop for the gaskets and keeps them from falling off the belt. Belt 49 is continuously driven by a pulley wheel 55 to which power is applied from any suitable source. On table 48 is a box 120 56 for receiving imperfect gaskets. Extending from the end of belt 49 which is adjacent the punch press down to the lower die structure is an inclined trough 57 having side walls 58 and a top wall 59 such 125 130

trough being of a size to let a single row of gaskets slide down it, directing them into groove 18 in die member 16. Projecting up through a slot in the bottom of trough 57 is 5 a star wheel 60 carried by a shaft 61 which is pivoted in posts 62 depending from the bottom of trough 57. On one end of shaft 61 is a ratchet wheel 63 having one tooth for each arm of the star wheel and engaging 10 the teeth of the ratchet wheel is a spring pawl 64 carried by a lever 65. One end of lever 65 is slotted so as to straddle wheel 63 and is pivoted on shaft 61, and at an intermediate point it is connected to reciprocating head 15 by an arm 66. As head 15 moves downward lever 65 will be lowered moving pawl 64 one tooth along ratchet wheel 63, and as head 15 moves back, lever 65 will be raised turning ratchet wheel 63, 15 shaft 61 and star wheel 60 an angular distance equal to the distance between the arms of the star wheel.

The operation of the feeding mechanism is as follows:—A supply of unfinished gaskets, as shown in Fig. 6 is placed in hopper 52 and an operator, standing at the side of the hopper feeds them by hand down wall 53 onto belt 49, placing them so the open side is up, any imperfect gaskets being put in box 56. Belt 49 runs in a direction to feed the gaskets into trough 57 and the operator puts gaskets on the belt fast enough to keep trough 57 well filled. The lowermost gasket rests against the arm of the star wheel which 20 is projecting up through the slot in the bottom of the trough, and as the star wheel is turned step by step by the reciprocating motion of head 15, a gasket is fed forward or released on each up stroke of the head. 25 When released the gasket slides down into the groove 18 of die member 16, pins 19 acting as a stop for it. Since the upper die structure on its return stroke carries the finished gasket with it, die member 16 is always ready to receive the next gasket.

With the foregoing machine, I am enabled to perform the operation described on successive gaskets at a very rapid rate and in an entirely automatic manner, the operator having only to place gaskets from hopper 52 onto belt 49, or in other words, feed them to trough 57. This is a simple manual operation and can be done by an unskilled person. The fact that the upper die structure 50 comprises means for carrying up with it the finished gasket and then ejecting it from between the die structures greatly increases the speed of the machine for a finished gasket is never in the way of the forward 55 movement of an unfinished gasket onto the lower die structure.

In accordance with the provisions of the patent statutes, I have described the principle of operation of my invention, together 60 with the apparatus which I now consider to

represent the best embodiment thereof, but I desire to have it understood that the apparatus shown is only illustrative and that the invention may be carried out by other means.

What I claim as new and desire to obtain by Letters Patent of the United States, is:

1. In combination, a stationary die structure, a movable die structure adapted to move into engagement with the stationary die structure to perform an operation on a device, yieldable catch fingers carried by the movable die structure for catching the device operated on and carrying it away with it, and means for automatically releasing 70 the catch fingers.

2. In combination, a stationary die structure, a movable die structure adapted to move into engagement with the stationary die structure to perform an operation on a device, means forming a part of the movable die structure for catching the device operated on and carrying it away with it, means for ejecting the device from the movable die structure, and means actuated by the movable die structure for feeding devices to the stationary die structure.

3. In combination, a stationary die structure, a movable die structure adapted to move into engagement with the stationary die structure to perform an operation on a device, means forming a part of the movable die structure for catching the device operated on and carrying it away with it, means for ejecting the device from the movable die structure, means for feeding devices to the stationary die structure, and automatic means actuated by the movable die structure for controlling said feeding means.

4. In combination, a stationary die structure, a movable die structure adapted to move into engagement with the stationary die structure to perform an operation on a device, yieldable catch fingers carried by the movable die structure for catching the device operated on and carrying it away with it, means for automatically releasing the catch fingers and means for directing an ejected device from between the die structures.

5. In combination, a stationary die structure, movable die structure adapted to move into engagement with the stationary die structure to perform an operation on a device, means forming a part of the movable die structure for catching the device operated on and carrying it away with it, means for ejecting the device from the movable die structure, means for directing an ejected device from between the die structures, and automatic means actuated by the movable die structure for feeding devices one at a time to said stationary die structure.

6. In a die structure, an inner die member having an operating surface, an outer die member slidably axially on the inner die

member and having an operating surface complementary to the operating surface on the inner die member, yieldable catch fingers carried by the inner die member for holding 5 a device which has been operated on, and means for removing the outer die member on the inner die member for ejecting a device from said catch fingers.

7. In a die structure for performing an 10 operation on a ring, an inner die member having an operating surface and a nose projecting beyond it, means carried by said nose adapted to pass through a ring and engage it so as to carry a ring along with the 15 die structure, an outer die member slidable on the inner die member and having an operating surface complementary to that on the inner die member, and means for moving the outer die member on the inner die member 20 for ejecting a ring from the die structure.

8. In a die structure for performing an operation on a ring, an inner die member having an operating surface and a nose projecting beyond it, provided with a transverse slot, catch fingers pivoted in said slot and having shoulders which project beyond the side of the nose, said shoulders being adapted to pass beyond a ring and carry it 30 along with the die structure, an outer die member slidable on the inner die member and having an operating surface complementary to that on the inner die member, and spring means for holding said surfaces 35 in alignment, said outer die member being adapted to move on said inner die member against the action of said spring to eject a ring off said shoulders.

9. In a die structure, a die member having 40 an operating surface, a yielding catch means carried by said member in advance of said

surface and adapted to engage a device to be operated on, and ejector means for ejecting a device off said catch means.

10. In a die structure for operating on a 45 ring, a die member having an operating surface and a nose projecting in advance of such surface and provided with a transverse slot, catch fingers pivoted in said slot and having shoulders adapted to pass through a 50 ring and project under it, and ejector means for forcing a ring off said shoulders.

11. In a punch press for performing an operation on a ring, a stationary die member having a central opening and a groove 55 surrounding it and adapted to receive a ring, a movable die structure having a part for performing an operation on a ring and a means which engages the ring to carry it along with the movable die structure, and an 60 ejector which is actuated when the movable die structure approaches the end of its return stroke for knocking the ring off the engaging means.

12. In a punch press for performing an 65 operation on a ring, a stationary die member having a central opening and a groove surrounding it and adapted to receive a ring, a movable die structure having a part for performing an operation on a ring and a 70 yielding catch means which passes through a ring and engages it to carry the ring along with the movable die structure, an ejector for knocking a ring off said catch means, and automatic means actuated by the movement of the movable die structure for feeding rings one at a time to the groove in said 75 stationary die member.

In witness whereof, I have hereunto set my hand this 30 day of April, 1920.

JOHN A. LUTHER
